TOY FISHERMAN

Lynn C. Kester, Hereford, Tex.

Application December 28, 1945, Serial No. 637,542

4 Claims. (Cl. 46—119)

1

This invention relates to a toy fisherman, and it is one object of the invention to provide a toy consisting of a figure representing a man seated upon a log and holding a fishing rod in his hand, the arms being pivotally mounted so that when pull is exerted upon a line carried by the fishing rod, the arms will be swung downwardly, the arms being connected with the eyes and mouth of the fisherman's head so that as the arms are swung downwardly the mouth will be opened and the eyes pushed forwardly to a protruding position and thus indicate a surprised expression over catching a large fish.

Another object of the invention is to provide a toy of this character wherein the arms are fixed to the ends of a crankshaft which passes thru the body of the figure, the crank of the shaft having pivoted thereto a rod for operating the eyes and the mouth and this crank being engaged by a spring which will return the arms and the mouth and eyes to a normal position when pull upon the line is released.

Another object of the invention is to provide a toy of this character wherein the log upon which the figure is seated has its ends cut straight across so that the end faces of the log may be used for advertising purposes or for slogans.

Another object of the invention is to provide a toy fisherman which is of simple construction and not liable to become broken easily or get out of working order.

The invention is illustrated in the accompanying drawing, wherein—

Figure 1 is a perspective view of the improved toy fisherman, portions being in section.

Figure 2 is a fragmentary sectional view taken transversely through the body of the fisherman along the line 2—2 of Figure 1.

Figure 3 is a view of the forked member having eyes at ends of the arms, and

Figure 4 is a perspective view of the lower jaw and its mounting arm.

The log 1 which constitutes a base for the toy may be formed of metal, wood, plastic, or other suitable material, and has its ends cut straight across to provide flat end faces 2 upon which advertising matter or slogans may be applied. The figure 3 represents a fisherman seated upon the log 1 and this figure may be formed of metal or other suitable material. The figure has a body 4, legs 5, a neck 6, and a head 7, and at opposite sides of the body there have been provided arms 8 which project forwardly therefrom and terminate in hands 9 holding a fishing rod 10.

2

A line 11 extends downwardly from the front end of the rod 10 and at its lower end carries a hook 12 from which a representation of a fish may be suspended if so desired. It will be understood that the figure may be secured in seated position upon the log in any desired manner, or it may be formed integral with the log in case the log and the figure are formed of plastic or other molded material.

10 In order to pivotally mount the arms 8, there has been provided a shaft 13 which extends transversely through the body with its ends protruding therefrom and the arms are rigidly mounted upon the protruding end of the shaft 13 so that when the arms are swung downwardly by pull upon the line 11, the shaft will be turned. This shaft has a rearwardly extending crank 14 to which is pivotally connected the lower end of a rod or link 15 which extends upwardly through 15 the neck 6 and at its upper end is pivotally connected with a lever 16. The lever 16 projects rearwardly from the lower jaw 17 of the head 7 and since the lower jaw is pivotally mounted at its junction with the lever 16, as shown at 18, 20 upward movement of the link or rod 15 will tilt the lever 16 upwardly and the jaw 17 will be swung downwardly and open the mouth 19. An arm 20 extends upwardly from the lever 16 and at its upper end this arm is connected with a 25 rod 21 which extends forwardly and at its front end carries eyes 22 normally disposed in a natural position in the eye-receiving openings 23 of the head. When, however, the lever is swung upwardly and the arm 20 moves upwardly and forwardly during tilting of the lever 16 about the pivot 18, the rod 21 will be shifted forwardly and the eyes will be caused to protrude outwardly a slight extent and impart a surprised appearance to the fisherman. When pull upon the line 30 11 is released, the arms and the lower jaw and the eyes must be returned to the normal position, and in order to do so there has been provided a spring 24 consisting of a strip of resilient metal which is curved longitudinally and has its lower end secured to the back of the figure by a fastener 25 and its upper end portion disposed in overlapping engagement with the crank 14. The spring is straightened somewhat by having its upper end portion flexed upwardly and rearwardly during upward movement of the crank 14, and when pull upon the line is released, the spring returns to its original shape and downward pressure upon the crank will rotate the shaft 13 and cause the arm to be swung upwardly to the initial position, and downward pull 35 40 45 50 55

exerted upon the link 15 so that the lower jaw 17 will be closed and the eyes returned to the normal position.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to, in actual practice, if desired.

Having thus described the invention, what is claimed is:

1. A device of the character described comprising a base, a figure supported upon the base, in seated position and having a body formed with a neck and head at its upper end, the head having eye openings and having a lower jaw pivotally mounted for opening and closing movement, a shaft extending through the body with ends protruding from opposite sides thereof and within the body being formed with a rearwardly extending crank, arms fixed to the protruding ends of the shaft and extending forwardly and having hands at their front ends, a fishing rod carried by the hands of said arms and provided with a depending line at its front end, a lever extending rearwardly from the pivoted jaw, a link extending vertically through the neck and having its lower end pivoted to the crank of said shaft and its upper end pivoted to the rear end of said lever, an upright member extending upwardly from said lever, a member in the head extending horizontally between front and rear portions of the head and having its rear ends connected with the upper end of the upstanding member and provided at its front end with eyes movable through the eye openings of the head from a normally retracted position to a forwardly protruding position when the lever is swung upwardly and the jaw swings downwardly to an open position, and a strip of resilient metal secured at one end to the back of the body and extending upwardly and forwardly with its upper end portion overlapping the crank to yieldably hold the crank in a normal position and yieldably hold the arms in a normal position and the jaws closed and the eyes in their normal position.

2. A device of the character described comprising a figure representing a fisherman and having a body provided with a neck and head at its upper end, the head having eye openings and

provided with a lower jaw pivotally mounted for opening and closing movement, a crank shaft rotatably mounted through the body, arms fixed to end portions of said shaft and extending forwardly therefrom in position for holding a fishing rod, a lever extending rearwardly from the pivoted jaw, a link connecting the rear end of said lever with the crank of said crankshaft, an upstanding arm carried by said lever, eyes movable through the eye openings from a normally retracted position to an extended position and connected with the upstanding arm to effect such movement during movement of said lever for opening and closing the lower jaw, and a strip of resilient metal curved longitudinally and disposed vertically in the body with its lower end secured to the back of the body and its upper end overlapping the crank of the crankshaft to yieldably hold the crankshaft in a normal position and yieldably hold the arms and the lower jaw and the eyes in a normal position.

3. A device of the character described comprising a figure having a body provided with a neck and head at its upper end, a crankshaft rotatably mounted through the body, arms fixed to said crank shaft and projecting forwardly from the body, the head having eye openings and being provided with a lower jaw mounted for opening and closing movement, a lever extending rearwardly from the lower jaw, a spring member engaged with the crankshaft and yieldably holding the same in a normal position with the arms raised and the lower jaw closed, and eyes movable through the eye openings of the head and connected with said lever for movement from a retracted position to a forwardly protruding position when the jaw is moved to an open position.

4. A device of the character described comprising a figure including a body having a neck and head at its upper end, the head being provided with eye openings and having a lower jaw mounted for opening and closing movement, arms at opposite sides of said body, eyes movable through the eye openings from a normal position to a forwardly protruding position, means for mounting the arms for swinging movement from a normally raised position to a lowered position, said means being connected with the lower jaw and the eyes for opening the lower jaw and moving the eyes forwardly to a protruded position when the arms are lowered, and spring means yieldably holding the arms, and the jaw and the eyes in a normal position.
